GRINDING MACHINE RAPID ADVANCE MOTOR
Jacob Decker, Cincinnati, Ohio, assignor to The Cincinnati Milling Machine Company, Cincinnati, Ohio, a corporation of Ohio

Filed Sept. 7, 1960, Ser. No. 54,440

1 Claim. (Cl. 51—165)

This invention relates to a machine tool infeed mechanism and is particularly suitable for a precision grinding machine arranged to operate in an automatic cycle.

For automatic cycle, a grinder usually is provided with a rapid movement and a feeding movement of the wheelhead. Rapid advance movement eliminates working clearance between the grinding wheel and workpiece while rapid retraction movement provides the working clearance after a grinding operation is completed. The feed movement takes place during the cutting portion of the grind cycle. A hydraulic piston and cylinder is generally used in the plain and angular slide types of hydraulic grinders equipped for automatic cycle to provide axial translation of a crossfeed screw during the rapid movement. The crossfeed screw is then rotated by a feed motor to provide the feed movement. Although this is a practical and successful mechanism for these machines, it has not proved to be adaptable to the universal type grinder which is distinguished in one respect from the plain and angular slide machines by its wheelhead which is mounted on a swivel base to allow for angular adjustment of the cutting surface of the wheel relative to the axis of a workpiece. It is desirable to provide an automatic cycle for the universal grinder, however, even though serious limitations are imposed on the infeed mechanism of such an automatic universal grinder. The mechanisms must not interfere with the swivel mounting of the wheelhead and should not substantially add to the shop space required for operation of the machine. Therefore, conventional use of the crossfeed screw is inconvenient since it limits the swivel movement of the wheelhead. The hydraulic piston and cylinder adds bulky structure to the rear of the machine and becomes impractical as a means for furnishing rapid translation of the feed mechanism.

It is therefore an object of this invention to furnish an infeed mechanism which does not interfere with the swivel mounting of a universal grinder wheelhead.

It is a further object to supply an infeed mechanism for an automatic cycle machine which can be contained within the base of the machine with no resulting increase in bulk of the machine which would cause additional shop space requirements.

Other objects and advantages of the present invention should be readily apparent by reference to the following specification, considered in conjunction with the accompanying drawings forming a part thereof, and it is to be understood that any modifications may be made in the exact structural details there shown and described, within the scope of the appended claim, without departing from or exceeding the spirit of the invention.

When constructed in accordance with the preferred form of this invention, a grinder infeed mechanism utilizes a rack and pinion drive, the rack being fixed to the wheelhead and the pinion being fixed on a rotatable drive shaft supported in the machine base on which the wheelhead is received. This rack and pinion arrangement provides both the rapid movement of the wheelhead toward and away from the workpiece and also the slower feed movement. The pinion is connected to the feed motor by a driving train which includes, between the feed motor and the pinion, a rapid advance motor so that the pinion can be driven either by opera-

2

tion of the rapid advance motor or by operation of the feed motor through the rapid advance motor. The drive shaft rotates around a fixed axis and by placing the axis about which the wheelhead is made to swivel on this same axis, the engagement between the drive shaft and the wheelhead can be maintained for any angular position of the wheelhead. The rapid rotation of the drive shaft producing rapid movement of the wheelhead is provided by a paddle type motor. The body of the motor is carried on the drive shaft. The drive shaft extends into the motor body where a paddle extending from the shaft is received for limited rotary movement. The motor body is easily contained within the base of the machine where the drive shaft is supported. When the paddle is rotated to produce rapid movement, this motor body is in a fixed position relative to the base, but during feed movement it rotates with the drive shaft. The feed power is furnished by a separate feed motor during feed but which is utilized as a brake mechanism to restrain rotation of the body of the paddle motor when that motor is operated.

A clear understanding of the construction and operation of this invention may be obtained from the following detailed description and the attached drawings wherein:

FIG. 1 shows a universal grinding machine with portions broken away for clarity.

FIG. 2 is a sectional view of the infeed mechanism of the grinder in FIG. 1 on line 2—2.

FIG. 3 is a section of FIG. 2 on line 3—3.

FIG. 4A and FIG. 4B show the hydraulic feed circuit of the machine.

FIG. 5A and FIG. 5B show the electrical control circuit for the feed mechanism.

FIG. 1, a universal grinding machine is shown which has a wheelhead 10 mounted on an intermediate member 12. The intermediate member has a way 14 on which the wheelhead moves toward and away from the table 16 on which the workpiece (not shown) is supported. The intermediate member 12 is received on the base 18 of the machine and is pivotally adjustable thereon. The exposed portion of FIG. 1 shows the location of the feed mechanism which is contained in the base 18 by the motor enclosure portion 20 of the base. The cross feed shaft 22 extends through the motor enclosure portion to the front of the machine where it is geared to a handwheel assembly 106 (FIG. 4B) and the hydraulic feed motor 118, located at the front of the machine below the table.

The section view in FIG. 2 shows the structural details of the paddle motor. The wheelhead 10 which carries a grinding wheel 24 and guard 26, is located on the ways 14 in the intermediate member 12. The intermediate member is located on the top of base 18 and is pivotally adjustable on the swivel surface 28. A rack 30 is fixed to the wheelhead 10 and extends parallel to the ways 14. The rack is engaged by split pinion 32. The lower part 32a of the split pinion is fixed to a drive shaft 34 and the upper part 32b is fixed to a torsion bar 36. The torsion bar is received through the drive shaft 34 and has secured thereto a clamp 38 held against rotation relative to drive shaft 34 by pins (not shown). The torsion bar and drive shaft 34 have a relative twist which is preserved by the split pinion being engaged with the rack on one end and the clamp 38 on the other end. This twist eliminates backlash between the rack and pinion. The drive shaft is supported in the motor enclosure portion 20 of the base 18 in tapered annular bearings 40 and 42. The housing or body of the paddle motor 43 is comprised of a top member 44, a middle member 46, and a lower member 48 on which a worm wheel form has been machined. The body is received on the shaft 34 and held

in place by nuts 50 and 52. The drive shaft 34 is rotatable in limited amount relative to the body in annular bearings 54 and 56. These bearings 54 and 56 also hold the shaft and body rigidly concentric relative to each other. The worm wheel form of the lower portion 43 of the motor body is engaged by a worm 58 which is fixed on the crossfeed shaft 22.

FIG. 3 shows a cross section of the paddle motor received on the drive shaft 34. The motor body encompasses a cavity 62 which is concentric with the shaft 34 and has a radial wall member 64 fixed therein. This wall, which is connected to member 46 limits the cavity 62 to an angular arc of less than 360 degrees around the shaft. Extending from the shaft is the paddle segment 66 which is fixed to the shaft and received in the cavity. The paddle segment may be swung within the limits of the cavity 62 from one side of the wall 64 to the other to produce the limited rotary movement of the shaft 34 relative to the body of the motor 43. Positive stops 68 are fixed in each side of the wall 64 to engage stop pads 70 of the paddle segment 66 as that segment is caused to move from one end of the arcuate cavity to the other end. Fluid under pressure is selectively supplied to the cavity through ports 72 and 74 in the shaft 34 which are terminal ends of fluid lines 76 and 78 (FIG. 2) and the ports 64a (the port including an adjustable ball restriction in the wall member 64). Lines 76 and 78 are selectively connectable to a source of fluid under pressure and to drain to supply fluid under pressure to the cavity 62 between the paddle segment 66 and one side of the wall member 64 and to remove fluid from the cavity between the paddle segment and the other side of the wall member. This causes the paddle segment to swing within the cavity from engagement with one side of the wall member 64 to engagement with the other side. In swinging, the paddle segment rotates the drive shaft 34 to which it is fixed.

FIG. 4A and FIG. 4B show the hydraulic circuit of the grinding machine described. The hydraulic pump P and relief valve RV are assumed to be in operation as are all of the electrical elements of the machine. To initiate the cycle, a lever 80 (FIG. 4B) of the cycle start valve 82 is pulled forward and the full pressure line 84 is connected to a hydraulic line 86 connected to the pressure switch 5PS. Conversely, pushing lever 80 in the opposite direction connects pressure line 84 to line 85. This will operate pressure switch 4PS and terminate automatic cycling. Upon the operation of the pressure switch 5PS, solenoid 1SOL (FIG. 4A) is energized to shift the plunger of valve 94 down. Fluid lines 84 and 88 are connected and lines 90 and 92 are connected in the wheelhead control valve 94. Line 92 connects through valve 168 to the drain line 124. Pressure is connected through the selector valve 96 (FIG. 4A) from line 88 to line 98 and the shifter bracket 100 (FIG. 4B). Line 174 is connected through valve 96 (FIG. 4A) to line 90 which is now connected to the main return line 92. The fluid is allowed to escape from the right side of the shifter 100 (FIG. 4B). The shifter moves to the right and meshes gear 102 with gear 104 in the handwheel mechanism 106. Gear 104 is mounted to rotate gear 108 which in turn is meshed with gear 110 on the end of the crossfeed shaft 22. The worm gear 58 is fixed on the shaft 22 and is engaged with the worm wheel form on the portion 43 of the paddle motor. Gear 102 is attached to rotate with the shaft 112 which has a worm wheel 114 driven by the worm gear 116. The worm gear 116 is driven by the hydraulic feed motor 118 through gears 120 and 122. As long as the hydraulic feed motor is maintained in a static condition the paddle motor body of the paddle motor 43 (FIG. 2) will not be allowed to turn since the described gear train and hydraulic feed motor are all mechanically connected and furnish a braking mechanism to oppose rotation of the paddle motor body. When switch 5PS is closed, fluid under pressure is also supplied from line 84 through valve 94 to line 88 which connects

to fluid passage 76 (FIG. 2). That line opens through port 72 (FIG. 3) to the cavity in the paddle motor on one side of the paddle segment 66 which swings to rotate shaft 34. At the same time, fluid line 90 which connects to fluid passage 78 (FIG. 2) opening through port 74 (FIG. 3) to the cavity on the other side of the paddle segment and line 92 (FIG. 4A) are connected through the wheelhead control valve 94. The by-pass valve 168 is in a position connecting line 92 to the return line 124 and the fluid on the other side of the paddle segment 66 is allowed to escape to the reservoir. The paddle segment swings within the angular space of the cavity and effects rapid rotation of the drive shaft 34 (FIG. 2). When the drive shaft rotates, the wheelhead is moved along the ways in the intermediate member of the machine base. Thus, the paddle motor operates as a lost motion mechanism in the driving train between the feed motor 118 and the wheelhead 10 to produce a fixed amount of rapid movement of the wheelhead. When the paddle segment completes its swing, the rapid advance movement is stopped, and the pressure switch 3PS (FIG. 4A) is operated. Pressure continues to be supplied to the paddle motor through line 92 however. This holds the paddle segment against the wall in the motor housing and the paddle motor becomes a rigid part of the driving train.

When pressure switch 3PS is operated solenoid 2SOL is energized and the plunger of the pilot valve 126 is caused to shift left and pressure from line 84 is applied to line 128. The plunger of the motor cut-off valve 130 shifts right when pressure is in line 128. Line 132 is connected to line 134. At the same time, the plunger of the pilot valve 136 has shifted left since solenoid 4SOL is also energized when pressure switch 3PS is operated and pressure from line 84 is connected to line 138 to shift the plunger of the fast rate cut-off valve 140 to the right. At this time lines 88 and 144 are connected in the pressure reducing valve 142. Fluid under pressure moves through the pressure reducing valve 142 to line 144. From there, the reduced pressure fluid goes through the check valve 146, line 134, valve 139, line 132 to the motor reversing valve 148 where it connects to line 150. Line 150 connects with the hydraulic feed motor 118 (FIG. 4B). This motor now rotates and drives gears connected to the handwheel mechanism 106 which turns the crossfeed shaft 22 and the worm 58 (FIG. 2) to effect rotation of the paddle motor body 43 and the drive shaft 34 to produce a feed movement of the wheelhead on the ways toward the table 16 (FIG. 1). Fluid is exhausted from the feed motor 118 (FIG. 4B) by way of fluid line 152 which connects with line 154 in the motor reversing valve 148 (FIG. 4A). Line 154 carries the fluid to the fast rate cut-off valve 140 the plunger of which has shifted to the right to connect lines 154 and 156. The return fluid from the feed motor passes through the fast grind rate valve 158 to the return line 124 draining to the fluid reservoir. The setting of the fast grind rate valve then controls the wheelhead feed rate for the first period of the grinding cycle.

After a predetermined amount of feed movement, solenoid 4SOL is deenergized and the plunger of the fast rate valve 140 is shifted to the left. Line 154 is blocked from the fast grind rate valve causing the return fluid to pass through the filter 160 and the slow feed rate valve 162 to return line 124 which provides a second and slower feed movement of the wheelhead. After a small amount of feed at this slower rate, the feed is stopped completely by a positive stop (not shown) engaged by the handwheel mechanism 106. After a predetermined time, solenoid 1SOL is deenergized and the plunger of the wheelhead control valve 94 is caused to shift back to the position shown. Lines 84 and 90 are connected and lines 88 and 92 are connected. This reverses the fluid pressure differential in the paddle motor 43 and the paddle segment 66 swings rapidly back to its initial position.

The rotation of the drive shaft 34 (FIG. 2) is reversed and the wheelhead rapidly retracts from the workpiece, the amount of retraction being equal but opposite to the rapid advance movement. The feed motor 118 (FIG. 4B) and the gear train connecting to the paddle motor body again act as a brake to restrain the movement of the paddle motor body relative to the machine base. At the end of the rapid retraction, the fluid pressure differential in the paddle motor holds the motor body and drive shaft in a relatively fixed relationship.

When the plunger of the wheelhead control valve 94 changes its position to connect lines 88 and 92, and lines 84 and 90, pressure through line 90, the crossfeed selector valve 96, and line 174 attempts to move the shifter bracket 100 (FIG. 4B) to the left, tending to engage gears 164 and 110 to reverse rotation of the crossfeed shaft 22. At the same time, the pressure in line 90 is causing the plunger in the reversing valve 148 (FIG. 4A) to move upward to the position shown at a rate controlled by the restriction 166. During the shift, lines 132 and 152 and lines 156 and 154 are momentarily connected. This provides a momentary reversal of the feed motor 118 allowing the backlash between the gears 164 and 110 to be adjusted to allow these gears to mesh. Lines 132 and 150 and lines 154 and 152 are reconnected then and the fluid motor 118 again runs in the original direction. Solenoid 3SOL is energized at the same time that the rapid retraction takes place and the plunger of valve 171 shifts to the left to connect pressure line 84 to line 170. When pressure is in line 170, the plunger of valve 168 shifts left. Line 154 is connected to drain line 124. The feed motor 118 runs at a rapid rate now to restore the wheelhead to its starting position. Since at the start of the retraction stroke, the feed motor and rapid retraction motor may be both operating at the same time for a brief period, the worm wheel 114 (FIG. 4B) driven by the feed motor 118 is furnished with an overrunning clutch (not shown) to prevent the rapid retraction movement of the paddle motor from turning the hydraulic feed motor and causing interference with the normal motor action when the rapid retraction takes place.

The hydraulic feed motor runs until the wheelhead has reached its initial position relative to the work table and solenoids 2SOL and 3SOL are deenergized. The plunger of the motor cut-off valve is caused to move left and to block line 134 from line 132. The plunger of the rate valve by-pass valve 168 moves to the right to block line 154 from the return line 124 and the hydraulic system is returned to its initial static condition ready for another cycle.

The electrical control circuit for the wheelhead mechanism described is shown in FIGS. 5A and 5B. (Horizontal reference locations on FIGS. 5A and 5B will be indicated as a number prefixed with the letter Z and parenthesized herein.) To start the machine, the master start switch SW1 (FIG. 5A, Z29) is momentarily closed to connect relay 3M (Z20) across the control voltage lines LL1 and LL2 through closed contacts of the stop switch SW2 and contacts of switch SW1. Relay 3M is energized and picks up. The hydraulic pump motor MTR3 (Z6) is then energized through contacts of the relay 3M which connect the motor MTR3 to power supply lines L1, L2, L3. When the hydraulic pressure produced by the pump P (FIG. 4A) which is driven by motor MTR3 reaches a preset level, the pressure switch 1PS is operated and its contacts (FIG. 5A, Z23) are closed. Switch SW1 may be momentarily closed again to pick up the grinding wheel motor start relay 1M (Z23). When relay 1M is picked up, the grinding wheel motor MTR1 (Z3) is connected to power lines L1, L2, L3 through contacts of the relay 1M.

After the machine electrical circuits are energized and before the grinding cycle is commenced, a dog 180 (FIG. 4B) on the gearing of the internal portion 106a of the handwheel mechanism 106 operates the limit switch 1LS.

(The handwheel mechanism is geared to the feed motor such that the internal portion 106a rotates relative to the linkages 182, 184 as the feed motor 118 is operated. Also, with selector valve 96 (FIG. 4A) in the position shown, line 172 is not pressurized and the plunger 186 is forced down by the lever 183 and spring 190 to allow limit switch 1LS to be operated by the handwheel mechanism 106a. During setup, line 172 is connected to pressure line 84 through selector valve 96 to elevate plunger 186 and hold the limit switches 1LS and 2LS in their lower position as shown against an elevating bias force. In this condition limit switch 1LS operated and limit switch 2LS unoperated which puts the control circuit in a condition suitable for manual operation.) Relay 6CR (FIG. 5B, Z38) is picked up at the start of the cycle through contacts of the limit switch 1LS. The cycle start switch SW3 (FIG. 5B, Z25) may be closed now to start the grinding machine through a cycle of operation. When switch SW3 is momentarily closed, relay 1CR (Z25) is momentarily picked up through contacts of the pressure switch 4PS, cycle stop switch SW4 and switch SW3. (By pulling the lever 80 (FIG. 4B) forward, contacts of pressure switch SPS (FIG. 5B, Z26) are momentarily closed and will start the cycle as previously described by furnishing a by-pass circuit around the switch SW3.) When relay 1CR is up, the relays 2CR1 (Z27) and 2CR2 (Z28) are picked up through contacts of relays 1CR, 6CR, switch 4PS and the switch SW4. Relays 2CR1 and 2CR2 latch up through contacts of relay 2CR1 and the tarry timer 2TR (normally closed, time opened, instantaneous closed). When relay 2CR1 is up, solenoid 1SOL (Z16) is energized and shifts the wheel-head control valve 94 (FIG. 4A) plunger to start the rapid infeed movement of the wheelhead. The relay 2CR2 being up causes the motor control relay 5M to be picked up. When the relay 5M is up, the headstock motor MTR5 (Z9) is connected to lines L1, L2, L3 through contacts of relay 5M. Motor MTR5 rotates the workpiece during the grinding operation. Relay 2CR2 being up also causes relay 5CR (Z37) to be picked up through contacts of relays 2CR2 and 7CR (normally closed) and solenoid 4SOL (Z19) is energized through contacts of relay 5CR. This shifts the pilot valve 136 (FIG. 4A) left and a fluid return path is opened through the fast feed rate valve 158 from the feed motor 118 (FIG. 4B). At the end of rapid advance, pressure switch 3PS is operated and relay 3CR (FIG. 5B, Z29) is picked up through contacts of relays 7CR (normally closed) and 2CR2 and the pressure switch 3PS. Solenoid 2SOL (FIG. 5A, Z17) is energized through contacts of relay 3CR. The pilot valve 126 (FIG. 4A) shifts left and causes the motor cut-off valve 130 to allow fluid to flow through the hydraulic feed motor 118 (FIG. 4B). The feeding movement of the wheelhead begins. As the feeding movement begins, the handwheel mechanism 106 begins to rotate and the dog 180 moves to a position to allow limit switch 1LS (FIG. 5B, Z38) are opened and relay 6CR (Z38) is dropped. After a predetermined amount of feed movement, the limit switch 2LS (FIG. 4B) is operated as the roller 192 on the internal portion 106a of the handwheel mechanism 106 has been rotated to a position allowing the lever 184 to move up. The control relay 7CR (FIG. 5B, Z39) is picked up through contacts of limit switch 2LS. When relay 7CR picks up, relay 5CR (Z37) is dropped and solenoid 4SOL (Z19) is deenergized. The fast feed rate cut-off valve 140 (FIG. 4A) sends the return fluid from the feed motor 118 through the slow feed rate valve 162. The spark out timer 2TR (FIG. 5B, Z34) is started when relay 7CR is picked up and the contacts thereof in the timer circuit are closed. During the time that the timer 2TR is operating, the handwheel mechanism engages the positive stop (not shown) and further feed movement of the wheelhead is prevented. Shortly thereafter, the timer 75

2TR times out and relays 2CR1 (Z27) and 2CR2 (Z28) are dropped. Solenoid 1SOL (Z16) is deenergized and the wheelhead control valve 94 (FIG. 4A) is shifted to effect rapid retraction of the wheel head. Relay 5M is also dropped and the motor MTR5 is stopped.

The infeed motor is not stopped when relay 2CR-2 is dropped since a latch circuit exists through the normally closed contacts of relays 2CR2 and 6CR and contacts of relay 3CR which holds relay 3CR energized after the wheelhead has started retraction movement. At this time, after relays 2CR1 and 2CR2 have dropped, the plunger of the reversing valve 148 (FIG. 4A) is shifting and momentarily effects reversal of the feed motor 118 (FIG. 4B) to allow the gears 164 and 110 to mesh as the shifter 109 moves to the left. Relay 4CR (FIG. 5B, Z32) also picks up through contacts of relays 3CR and 2CR1 (normally closed) when relay 2CR1 is dropped. When relay 4CR is picked up, solenoid 3SOL (FIG. 5A, Z18) is energized through contacts of relay 4CR and the feed motor exhaust fluid is returned to the reservoir through the by-pass valve 168 (FIG. 4A). The feed motor 118 now drives the handwheel 106 and the worm gear 58 in the opposite direction to return the handwheel and wheelhead to their starting positions. During the return to the starting position, the internal portion 106a of the handwheel releases limit switch 2LS. When the wheelhead and handwheel have returned to their starting positions, limit switch 1LS is operated by the internal portion 106a of the handwheel mechanism 106. The contacts of limit switch 1LS (FIG. 5B, Z38) are closed and relay 6CR is picked up. When relay 6CR is picked up, relay 3CR (Z29) is dropped and solenoid 2SOL (Z17) and relay 4CR (Z32) are deenergized. When relay 4CR is deenergized, solenoid 3SOL (Z18) is deenergized. The electrical system and hydraulic system are now in their starting condition and the cycle may be begun again.

What is claimed is:

In a grinding machine having a source of fluid under pressure, a base, a wheelhead, and an intermediate member mounted on the base and pivotally adjustable thereon around an axis, said intermediate member having a way to

slidably receive the wheelhead, a mechanism to effect rapid and feed movements of said wheelhead on said way comprising in combination, a rack fixed on said wheelhead and parallel to said way, a drive shaft supported in the base for rotation on said axis, said drive shaft having a radial paddle segment extending therefrom and a bore therethrough, a torsion shaft received in said bore and extending therethrough concentric with said axis, a split pinion engaged with said rack having one portion fixed on said torsion shaft and another portion fixed on said drive shaft, means to maintain a predetermined relative twist between said drive shaft and torsion shaft operable to eliminate backlash between said rack and split pinion, a motor body received on said drive shaft and rotatable relative thereto having a worm wheel portion and a cavity therein concentric with said shaft, said cavity receiving said paddle segment and having a radial wall defining extreme angular positions of the paddle segment therein, said cavity having a port on each side of said wall, a shaft journaled in the base having a worm engaged with said worm wheel portion operable to control rotation of said motor body relative to said base, means selectively to connect said source of fluid under pressure to one of said cavity ports to swing said paddle segment to one of said extreme angular positions and rotate said drive shaft for rapid movement of said wheelhead on said way, a feed motor connected to said worm shaft to rotate said worm for rotation of said motor body and drive shaft to effect a feed movement of said wheelhead on said way after said paddle segment engages said wall, the paddle segment being held against said wall by said fluid under pressure at said one port, and means alternately to connect said other cavity port to pressure and to reverse said worm to retract the wheelhead.
